CLAIM

The ornamental design for a portable universal ground control system, as shown and described.

DESCRIPTION

FIG. 1 is a perspective view of a portable universal ground control system;

FIG. 2 is a front elevation view thereof;

FIG. 3 is a right side elevation view thereof;

FIG. 4 is a rear side elevation view thereof;

FIG. 5 is a left side elevation view thereof;

FIG. 6 is a top elevation view thereof; and,

FIG. 7 is a bottom elevation view thereof.

The broken lines shown in the drawings depict portions of the portable universal ground control system that form no part of the claimed design.
